UNITED STATES PATENT OFFICE

2,598,114

DEVICE FOR MARKING AND EJECTING
ELONGATED ARTICLESDavid I. Dilworth, Lorain, Ohio, assignor to
United States Steel Company, a corporation of
New Jersey

Application July 14, 1948, Serial No. 38,722

5 Claims. (Cl. 101—6)

1

This invention relates to improvements in devices for marking elongated articles, such as pipes or the like.

An object of the invention is to provide improved devices for marking the sides of elongated articles uniformly and in similar locations on succeeding articles.

A further object of the invention is to provide improved devices for marking the sides of elongated articles in which entry of an article into the device automatically starts the device, which then automatically marks and ejects the article.

A further object of the invention is to provide improved devices for marking the sides of elongated articles in which entry of an article to a predetermined position in the device automatically starts operation of a marking wheel, which then both marks the article and propels the article out of the device and resets so that it marks succeeding articles in similar fashion.

In accomplishing these and other objects of the invention, I have provided improved details of structure, a preferred form of which is shown in the accompanying drawings, in which:

Figure 1 is a top plan view of an improved marking device embodying features of the present invention;

Figure 2 is a side elevational view of the device shown in Figure 1;

Figure 3 is an end elevational view of the device shown in Figure 1;

Figure 4 is a vertical sectional view of the device taken substantially on line IV—IV of Figure 3;

Figure 5 is a side elevational view of a preferred form of marking wheel embodied in the device;

Figure 6 is a vertical sectional view of the marking wheel taken substantially on line VI—VI of Figure 5; and

Figure 7 is a wiring diagram of the preferred electrical circuit for operating the device.

Referring more in detail to the drawings:

The marking device of the present invention comprises a base 10 which may be mounted on any suitable table or sub-base 12 (Figures 2 and 3). The back portion of the base carries a motor stand 13 which preferably is welded to the base and is of inverted U-shape in end elevation. The sides of the stand have a series of mounting apertures 14 (Figure 2). A limit switch bracket 15 is supported between the arms of the U by suitable fastening means which pass through any of apertures 14, thus making possible adjustment of the longitudinal position of said bracket. An arm 16 of a normally open limit switch 17 is

2

pivoted to said bracket in a position to be engaged by the forward end of an elongated article S as it enters the device and thus to close the limit switch momentarily. A drive motor 18 is supported on the top of stand 13 and is positioned by adjustable positioning screws 19.

The forward portion of the base carries uprights 20, 21 and 22, which furnishes mountings for a supporting roll 23, a drive shaft 24 and an adjusting shaft 25 for varying the vertical position of the drive shaft. Preferably the three uprights are similarly constructed and each includes a boss 26 welded to base 10, a pair of spaced parallel posts 27 and 28 rigidly bolted to said boss; and a cap 29 rigidly bolted to the tops of said posts.

Supporting roll 23 is rotatably mounted in a cradle 30 between uprights 29 and 21. Said cradle is resiliently supported on base 10 by a spring 31, the compression of which may be varied through an adjusting screw 32. Stops 33 project inwardly from the posts of the uprights above the cradle and thus limit upward movement of the cradle and roll. Preferably the circumferential face of the roll is grooved to facilitate supporting and positioning cylindrical articles, such as pipes, for marking by the device.

Drive shaft 24 is rotatably mounted in bearings 34, which are supported for vertical movement between the posts of each upright (Figure 4). A drive pulley 35 is fixed to the drive shaft between uprights 21 and 22 and is connected to motor 18 by belts 36, preferably through suitable speed reducing mechanism embodied in the motor (Figures 1, 2 and 3). A marking wheel 37 is fixed to the drive shaft between uprights 20 and 21 and carries means for stamping or otherwise marking the sides of articles S. A cam limit switch 38 is connected to the end of the drive shaft. Said switch is supported on a shaft 39 which is outside upright 20 and is vertically movable with the shaft (Figure 3).

Figures 5 and 6 show the details of a preferred form of marking wheel. The wheel has a sector 37A of relatively large radius and a sector 37B of smaller radius. Sector 37A is adapted to receive removable stamps or other marking means. In the usual neutral position of the wheel, sector 37B is directed downwardly and the incoming article thus clears the wheel. On rotation of the wheel away from the neutral position, the stamps engage the article and mark it and propel it from the device.

Caps 29 furnish bearings for the adjusting shaft 25 (Figures 3 and 4). Each cap comprises

an upper section 40 and a lower section 41 rigidly bolted together. Preferably the caps on uprights 20 and 21 are bridged as shown at 42. The caps on uprights 20, 21 and 22 provide vertical bearings in which spindles 43 are rotatably mounted. The lower ends of said spindles have integral buttons 44 received in T-slots 45 in the upper faces of drive shaft bearings 34. Worm gears 46 have central bores threadedly engaged with spindles 43 between sections 40 and 41 of the caps. Worms 47 are fixed to the adjusting shaft and mesh with said worm gears. Preferably the end of shaft 25 carries a hand wheel 48.

It is seen that rotation of the adjusting shaft rotates worm gears 46 through worms 47. On account of the threaded engagement between the worm gears and spindles 43, rotation of the worm gears moves the spindles vertically in unison and thus raises or lowers the drive shaft and its bearings. This adjustment varies the spacing between marking wheel 37 and supporting roll 23 and thus adapts the device to receive articles S of differing sizes.

A motor brake 49 is operatively connected with motor 18 (Figure 1). Said brake may be of any suitable design that stops the motor as soon as the circuit is broken.

Figure 7 shows in detail a preferred electric circuit for operating the device. Motor 18 is connected to a power source through lines 50 and 51, which preferably contain a master switch 52. Brake 49 is connected across lines 50 and 51 in parallel with motor 18 via conductors 53 and 54. A solenoid 55 of a main line contactor is also connected across lines 50 and 51 in parallel with the motor and brake via a conductor 56 and either one of two alternative conductors 57 or 58. Line 50 and conductor 53 contain normally open contacts 59 and 60 respectively, which are operated together by solenoid 55. Conductors 57 and 58 contain limit switch 17 and cam limit switch 38 respectively.

It is seen that closing of limit switch 17, as when the end of an article engages arm 16, closes the circuit to solenoid 55 via line 50, conductor 56, conductor 58, switch 17 and line 51. Contacts 59 and 60 thereupon close and release brake 49 and start motor 18. As soon as the motor starts, cam limit switch 38 closes and thus maintains the circuit through solenoid 55 via conductor 57. Limit switch 17 opens as soon as arm 16 swings back. The motor rotates cam limit switch 38 via the pulleys and drive shaft and as soon as the drive shaft turns through one revolution, cam limit switch opens. The motor is thereupon stopped and the brake is again applied.

In operation, an elongated article S, such as a pipe, is inserted into the device and moved in until it strikes arm 16 of limit switch 17 closing the latter. As just explained, motor 18 thereupon commences rotating drive shaft 24. The marking wheel 37 in the drive shaft engages the side of the article and propels the article out of the device and applies a mark thereto. The resilient mounting of cradle 30 permits the roll and article to yield when irregularities on the article engage the marking wheel and thus avoids damage to the latter. Engagement of the end of the article with limit switch 17 insures that each successive article enters the apparatus the same distance. Since cam limit switch 38 stops after one revolution the device is automatically reset to mark successive articles in similar fashion.

From the foregoing description it is seen that I have provided an improved and simplified device for marking elongated articles such as pipes or the like. The markings can be applied expeditiously and be uniform and similarly located on successive articles.

While I have shown and described only a single embodiment of the invention, it is apparent that modifications may arise. Therefore, I do not wish to be limited to the disclosure set forth but only by the scope of the appended claims.

I claim:

1. A device for marking and ejecting elongated articles comprising means for movably supporting an article, a rotatable marking wheel spaced above said article supporting means and normally occupying a stationary position in which it clears an article moving along said article supporting means, means for driving said marking wheel, a limit switch spaced longitudinally from said marking wheel and adapted to be engaged by an end of the article supported on said article supporting means after a length of the article equivalent to the longitudinal spacing between said marking wheel and said limit switch passes said marking wheel, said limit switch being operatively connected with said driving means for starting rotation of said marking wheel on engagement of the limit switch by the article, said marking wheel on rotating from its normal stationary position engaging the article and simultaneously marking and ejecting the article by propelling it away from said limit switch, in a reverse direction from its previous movement, and an additional limit switch operated by said driving means when said marking wheel rotates back to its normal stationary position for stopping said driving means.

2. A device for marking and ejecting elongated articles comprising a base, uprights fixed to said base, a roll carried by said uprights for movably supporting an article, a rotatable marking wheel carried by said uprights and spaced above said roll and normally occupying a stationary position in which it clears an article supported on said roll, means for driving said marking wheel, a limit switch spaced longitudinally from said marking wheel and adapted to be engaged by an end of the article supported on said roll after a length of the article equivalent to the longitudinal spacing between said marking wheel and said limit switch passes said marking wheel, said limit switch being operatively connected with said driving means for starting rotation of said marking wheel on engagement of the limit switch by the article, said marking wheel on rotating from its normal stationary position engaging the article and simultaneously marking and ejecting the article by propelling it in the opposite direction away from said limit switch, and an additional limit switch operated by said driving means when said marking wheel rotates back to its normal stationary position for stopping said driving means.

3. A device for marking and ejecting elongated articles comprising a base, uprights fixed to said base, a roll resiliently carried by said uprights for movably supporting an article, a drive shaft spaced above said roll, bearings carried by said uprights for vertical adjustment and rotatably mounting said drive shaft, an adjusting shaft rotatably carried by said uprights and spaced above said drive shaft, gears and spindles operatively connecting said adjusting shaft and

said bearings for adjusting the spacing of said drive shaft above said roll, a marking wheel carried by said drive shaft and normally occupying a stationary position in which it clears an article supported on said roll, means for rotatably driving said drive shaft and said marking wheel, a limit switch supported by said base and spaced longitudinally from said marking wheel and adapted to be engaged by an end of the article supported on said roll after a length of the article equivalent to the longitudinal spacing between said marking wheel and said limit switch passes said marking wheel, said limit switch being operatively connected with said driving means for starting rotation of said drive shaft and said marking wheel on engagement of the limit switch by the article, said marking wheel on rotating from its normal stationary position engaging the article and simultaneously marking and ejecting the article by propelling it in the opposite direction away from said limit switch, and means automatically stopping said driving means when said marking wheel rotates back to its normal stationary position.

4. A pipe marking and ejecting device comprising a base, uprights fixed to said base, a roll carried by said uprights for movably supporting a pipe, a drive shaft spaced above said roll, bearings carried by said uprights for vertical adjustment and rotatably mounting said drive shaft, an adjusting shaft rotatably carried by said uprights and spaced above said drive shaft, gears and spindles operatively connecting said adjusting shaft and said bearings for moving said bearings and said drive shaft vertically and thereby varying the spacing between said drive shaft and said roll to accommodate different sizes of pipe, a marking wheel carried by said drive shaft and normally occupying a stationary position in which it clears a pipe supported on said roll, means for rotatably driving said drive shaft and said marking wheel, a limit switch supported by said base and spaced longitudinally from said marking wheel and forming a stop adapted to be engaged by a pipe moving past said marking wheel on said roll, said limit switch being operatively connected with said drive means for starting rotation of said drive shaft and said marking wheel on engagement of the limit switch by the pipe, said marking wheel on rotating from its normal stationary position engaging the pipe and simultaneously marking and ejecting the pipe by propelling it in the opposite direction away from said limit switch, and means automatically stopping said driving means when said marking wheel rotates back to its normal stationary position.

5. A pipe marking and ejecting device comprising a base, uprights fixed to said base, a roll resiliently carried by said uprights for movably supporting a pipe, a drive shaft spaced above said roll, bearings carried by said uprights for vertical adjustment and rotatably mounting said drive shaft, an adjusting shaft rotatably carried by said uprights and spaced above said drive shaft, gears and spindles operatively connecting said adjusting shaft and said bearings for moving said bearings and said drive shaft vertically and thereby varying the spacing between said drive shaft and said roll to accommodate different sizes of pipe, a marking wheel carried by said drive shaft and normally occupying a stationary position in which it clears a pipe supported on said roll, a stand on said base spaced from said uprights, a motor carried by said stand and operatively connected with said drive shaft, a limit switch carried by said stand and forming a stop spaced longitudinally from said marking wheel and adapted to be engaged by a pipe moving past said marking wheel on said roll, said limit switch being operatively connected with said motor for starting rotation of said drive shaft and said marking wheel on engagement of the limit switch by the pipe, said marking wheel on rotating from its normal stationary position engaging the pipe and simultaneously marking and ejecting the pipe by propelling it in the opposite direction away from said limit switch, and means automatically stopping said motor when said marking wheel rotates back to its normal stationary position.
